SUPERHETERODYNE RECEIVER

Rudolph H. Siemens, Richmond Hill, N. Y., assignor to Radio Corporation of America, a corporation of Delaware

Application January 11, 1937, Serial No. 119,926

6 Claims. (Cl. 250—20)

My present invention relates to superheterodyne receivers, and more particularly to a novel method of, and means for, increasing the frequency range of a short wave receiver by means of a fixed frequency oscillator.

It is generally known that it is relatively difficult to construct a sharply tuned superheterodyne receiver which will give satisfactory results when signals of a frequency higher than 30 megacycles (mc.) are to be received. One of the reasons for such difficulty resides in the fact that the heterodyne oscillator drifts in frequency. Various solutions for this problem can be proposed. However, they generally involve complicated devices, or circuits, which prohibit their usage in practical receivers.

One of the main objects of my present invention is to provide a superheterodyne receiver which embodies a local oscillator of fixed frequency utilizing accurate frequency control means; and the selection of signals being accomplished by means of a variable intermediate frequency (IF) amplifier whereby adequate stability of all circuits involved is provided and the selectivity characteristic secured is similar to that of receivers whose frequency range is limited to a maximum of 30 mc.

Another important object of the invention is to provide a superheterodyne receiver employing a first detector adapted to be tuned over a frequency range higher than 30 mc., a local oscillator of a fixed frequency of the order of 30 mc. being associated with the detector to produce signal energy over a wide range up to 30 mc.; and a variable IF amplifier and converter network being used to reduce the frequency of the resultant signal energy.

Another object of the invention is to improve generally the selectivity and operating efficiency of superheterodyne receivers, and more especially to provide a highly selective superheterodyne receiver which is capable of giving efficient operation for signals above 30 mc., and which receiver is not only readily and simply operated, but is economically manufactured and assembled.

The novel features which I believe to be characteristic of my invention are set forth in particularity in the appended claims; the invention itself, however, as to both its organization and method of operation will best be understood by reference to the following description taken in connection with the drawing in which I have indicated diagrammatically a circuit organization whereby my invention may be carried into effect. Referring now to the drawing there is shown

in a schematic manner the various networks of a superheterodyne receiver embodying my present invention; it being pointed out to those skilled in the art that the circuit details of the individual networks may embody arrangements well known to them. It is not believed necessary for the last named reason to show any of the circuit details of the different networks, since it is believed that those skilled in the art can readily supply such details with the following description. The receiving system embodies the usual signal collector A of any type. It is to be further understood that the signal energy received may be modulated with voice, or by pictures. In either case the collected signals are impressed upon the tunable input circuit 1 of the first detector 2. Of course one, or more, stages of tunable amplification could precede the first detector 2, and in which case the tuning devices of these preceding amplifiers would be adjustable with the tuning condenser 3 of the input circuit 1.

The detector 2 may employ a tube of any desired type, but it will be especially effective when it employs a tube which lends itself for the detection function in the operating signal range which covers 32 to 60 mc. inclusive. It will be understood, therefore, that the tuning condenser 3 is adjusted to vary the tuning of the input circuit 1 over a signal frequency range of 32 to 60 mc. inclusive. The first detector 2 is fed with locally produced oscillations from a local oscillator 4. The oscillator 4 is arranged to produce oscillations having a frequency of the order of 29.5 mc., and as a consequence there will be produced in the output circuit 5 of the first detector 2 IF energy in a range of 2.5 to 30.5 mc. It is not thought necessary to show the circuit details of the local oscillator 4, since it is well known how to construct an oscillator operating to produce energy of 29.5 mc. It is desired, however, that the local oscillator 4 be maintained at its frequency by means of an accurate frequency control device. For example, crystal control, or a very high Q tuned tank circuit, can be employed to fix the frequency of oscillator 4 accurately at its operating frequency. Since those skilled in the art are fully aware of the manner of accurately fixing the frequency of an electron discharge tube oscillator, it is not thought necessary to describe in any further detail the oscillator 4.

The IF energy produced in the output circuit 5 of the first detector is impressed on the tunable input circuit 6 of the first IF amplifier 7. The variable condenser 8 is adjustable to tune the input circuit 6 over a frequency range of 2.5 to 55

30.5 mc., the latter range including the intermediate energy frequencies produced by the heterodyne action of the fixed local oscillator 4 and the first detector when adjusted through its 5 tuning range of 32 to 60 mc. Of course, one or more tunable stages of IF amplification may be employed, and in such case the rotors of the tuning condensers will be mechanically uncontrolled with the rotors of condenser 8, and 10 the rotors of condenser 3. The numeral 9 denotes in dotted lines the mechanical uni-control mechanism which varies the rotors of the tuning condensers 3 and 8 in proper synchronism so that at any setting of the rotors of condenser 3, the 15 rotors of condenser 8 will be adjusted to tune input circuit 6 to the proper IF.

The signal energy, amplified by the first IF amplifier 7, is then impressed upon the tunable input circuit 10 of the second detector 11. The 20 variable condenser 12 has its rotors mechanically coupled to the rotors of condenser 8 so that the input circuit 10 is tunable over the IF range of 2.5 to 30.5 mc. The numeral 13 denotes a variable local oscillator which feeds local oscillations 25 to the second detector 11 so as to produce in the output circuit 14 of the second detector the second IF energy. The second IF energy is chosen to have a frequency of 1650 kc., and for this reason the second, or variable local oscillator, 30 13 is tunable over a frequency range of 4.15 to 32.15 mc.

The numeral 15 denotes the tunable tank circuit of the variable oscillator 13, and the tank circuit may include a variable condenser 16 35 whose rotors are arranged for mechanical uni-control, if desired, with the uni-control adjusting mechanism 9. In this way adjustment of the common control device 9 results in actuation of the rotors of condensers 3, 8, and 12 and 16 40 in synchronism so as to tune their respective resonant circuits to the predetermined frequencies. The oscillator 13 may be of any desired construction, and it may feed the locally produced oscillations to the second detector 11 45 in the same manner as the oscillations from network 4 are fed to the first detector 2. It is to be clearly understood that instead of utilizing separate detector and local oscillator tubes, each converter network may comprise a single tube 50 having its circuits arranged to provide a composite oscillator-detector circuit. Such composite circuits are well known to those skilled in the art, and tubes of the 6A7 type, for example, may be used in this connection.

The beat energy produced in the output circuit 14 of the second detector 11 is transferred to the resonant input circuit 18 of the second IF amplifier network 17. Each of circuits 14 and 18 is tuned to the second IF of 1650 kc., and it 60 will be understood that the network 17 may comprise one, or more, stages of amplification. Of course, if more than one stage of amplification 17 is used, then each of the second IF circuits will be tuned to the operating IF of 1650 kc. The 65 amplified second IF energy is impressed upon a third detector, or audio demodulator, 19 by means of the network 18, and the latter may be a transformer which has its primary and secondary circuits each resonated to the operating second IF. The third detector 19 may be of the usual detector construction, and, if desired, an 70 audio amplifier may be utilized in this circuit. Of course, the direct current voltage component of the finally detected signal energy may be employed for automatic volume control of preceding

signal transmission tubes; such AVC arrangements are too well known to warrant further description. The audio voltage component of the finally detected signal energy may be impressed upon one, or more, stages of audio amplification, and then utilized in any desired manner. The final utilization device may be a reproducer for sound or sight.

The arrangement shown herein will provide adequate stability of all circuits involved, and give results similar to present types of receivers whose frequency range is limited to a maximum of 30 mc. The circuits between input circuit 6 and the demodulator 19 may be those of the usual double detection superheterodyne receiver of the all wave type, and in such case the circuit between network 6 and demodulator 19 would be the aforesaid receiver when adjusted for short wave reception. In other words, the tunable radio frequency input circuits of such a short wave receiver would be used as the variable first IF amplifier circuits of the system shown in the drawing. In this way it becomes possible to use a receiver limited to a maximum frequency of 30 mc., in a higher range extending up to a frequency value as high as 60 mc. Furthermore, this is accomplished with minimum additional circuit elements.

Another advantage of the present system resides in the fact that the ratio of image rejection is never less than the minimum image ratio of the variable IF amplifier 7. This, of course, applies to interference frequencies differing by +3.3 mc. of the desired signal for the case described above. Such interfering signals would be given the same attenuation, due to the selectivity of the first IF amplifier, as lower frequency signals which are within the range of the first IF amplifier. An illustration of this effect follows:

Suppose the image ratio of the first IF amplifier to be 1000:1 at 30.5 mc. and 10,000:1 at 2.5 mc. This would permit the reception of signals which are combined with the fixed oscillator 4, of 60 mc. and 32 mc. respectively. The image signals of 63.3 mc. and 35.3 mc. would be attenuated to the same extent as signals received on the IF amplifier alone of 33.3 mc. and 5.8 mc. This increased image ratio would not be possible if the 32 and 60 mc. signals were received directly in the first IF amplifier 7. The image ratio probably would fall to 500:1 at 60 mc. and 1,000:1 at 32 mc., due to the loss of selectivity of the first IF amplifier 7 at these frequencies.

Again, there exists an advantage in the present system in that the gain at 32 to 60 mc. is practically the same as the first IF amplifier gain at 2.5 and 30.5 mc. This, of course, would not be possible if the first IF amplifier 7 were tuned directly to the 32-60 mc. range. The selectivity of the input circuit 1 (32-60 mc.) for image reduction purposes is likely to be adequate, since there is a large difference between the desired and undesired frequencies. An illustration of this is as follows: For a 60 mc. input the image frequency is 1 mc., where as for a 32 mc. input 65 it is 27 mc. A mechanical advantage is, also, secured in the present system in that a 4:1 ratio vernier dial action over the 32-60 mc. band is secured, if the 2.5-30.5 mc. range of the first IF amplifier is divided into four separate bands.

It is preferred that the receiving networks employed with the oscillator 4 be well shielded and electrically isolated from it. In such case no undue interference will occur between the oscillations produced by oscillator 4 and the high fre- 75

5 quency energy in the remaining circuit, or with signals in the 32-60 mc. band. One point of interference may occur when receiving a signal at 59 mc. At that point the fixed oscillator operating at 29.5 mc. coincides with the tuning of the first IF amplifier 7. This interference can be reduced, or eliminated entirely, by the use of a push-pull input to the first IF amplifier 7, in the manner disclosed and claimed by W. A. Harris 10 in his application Serial No. 748,606, filed Oct. 17, 1934, and granted on April 21, 1936, as Patent No. 2,038,285.

15 While I have indicated and described a system for carrying my invention into effect, it will be apparent to one skilled in the art that my invention is by no means limited to the particular organization shown and described, but that many modifications may be made without departing from the scope of my invention, as set forth in 20 the appended claims.

20 What is claimed is:

25 1. A method of superheterodyne reception which includes the steps of selecting a desired signal frequency from within the 32 to 60 megacycles range, beating such signal with oscillations of an accurately controlled frequency of 29.5 megacycles to produce an intermediate frequency range of 2.5 to 30.5 megacycles, beating the intermediate frequency energy so produced with local oscillations varying in frequency from 4.15 to 30.15 megacycles to produce a second intermediate frequency energy of 1650 kc., and demodulating the second intermediate frequency energy.

30 2. In a triple detection superheterodyne receiver, the combination of a first detector circuit including a highly selective input circuit resonant to signal frequencies in a range above 30 megacycles, a local oscillator operating at a fixed frequency which is of a value such that its oscillations heterodyne with the signals impressed on 35 said first detector to produce a range of intermediate frequency values below 30 megacycles to above 2 megacycles, an adjustable converter network constructed and arranged to convert energy in said intermediate frequency range to a second intermediate frequency energy of a frequency value of less than 2 megacycles, and means for detecting the second intermediate frequency energy.

35 3. In a triple detection superheterodyne receiver, the combination of a first detector circuit including a highly selective input circuit resonant to signal frequencies in a range above 30 megacycles, a local oscillator operating at a fixed frequency which is of a value such that its oscillations heterodyne with the signals impressed on 40 said first detector to produce a range of intermediate frequency values below 30 megacycles to above 2 megacycles, an adjustable converter network constructed and arranged to convert energy in said intermediate frequency range to a second

45 intermediate frequency energy of a frequency value of less than 2 megacycles, means for detecting the second intermediate frequency energy, and means for controlling the tuning of said first detector and converter network in unison through 5 their respective frequency ranges.

50 4. In a superheterodyne receiver, a first detector having a highly selective input circuit resonant to signal frequencies in the signal range of 32 to 60 megacycles, a frequency controlled 10 local oscillator, coupled to said first detector, constructed to operate at an accurately fixed frequency value of 29.5 megacycles, a first intermediate frequency amplifier having means for tuning it through a frequency range of 2.5 to 30.5 15 megacycles, a second detector having means for tuning it through a frequency range equal to the frequency range of said intermediate frequency amplifier, a second local oscillator having means for tuning it through a frequency range which 20 differs from the frequency range of said second detector by a substantially constant second intermediate frequency value of 1650 kc., and means for detecting the second intermediate frequency 25 energy.

55 5. Apparatus for adapting a short wave receiver of the superheterodyne type designed to receive signals in a certain frequency range to one capable of receiving signals in a higher frequency range, comprising a detector circuit having a highly selective input circuit tunable through said range of higher frequencies, a fixed frequency local oscillator coupled to said detector circuit to produce an intermediate frequency which varies depending upon the tuning 30 of the detector input circuit, said variable intermediate frequencies lying in the range of frequencies for which the receiver is designed, and an output circuit for feeding said variable intermediate frequencies to the input of the receiver 35 proper.

60 6. Apparatus for adapting a short wave receiver of the superheterodyne type designed to receive efficiently signals in the frequency range between 2.5 to 30.5 megacycles to one capable of 45 efficiently receiving signals in the frequency range between 32 to 60 megacycles, comprising a detector circuit having a highly selective input circuit tunable through said last mentioned range of frequencies, a local heterodyne oscillator producing oscillations at the fixed frequency of 29.5 megacycles coupled to said detector circuit to produce an intermediate frequency which varies depending upon the tuning of the detector input circuit, said range of intermediate frequencies lying in the range of frequencies for which the receiver is designed, and an output circuit for feeding said variable intermediate frequencies to the input of the receiver proper.
